COMBINED ILLUMINATOR AND MAGNIFYING DEVICE

John R. Knoetgen, 20 Bailey Ave.,
Bay Shore, N.Y. 11706

Filed Apr. 30, 1969, Ser. No. 16,958

Term of patent 7 years

Int. Cl. D16—08

U.S. Cl. D57—1

FIG. 1 is a perspective view of a combined illuminator and magnifying device showing my new design;

FIG. 2 is a top plan view thereof;

FIG. 3 is a front elevational view thereof;

FIG. 4 is a bottom plan view thereof;

FIG. 5 is a back elevational view thereof; and

FIG. 6 is a left side elevational view thereof.

The side opposite that shown is substantially the same as the side that is shown.

I claim:

The ornamental design for a combined illuminator and magnifying device, substantially as shown and described.
